UNITED STATES PATENT OFFICE.

WILLIAM POUNTNEY, OF PORT JERVIS, NEW YORK.

DESIGN FOR A BOTTLE.

SPECIFICATION forming part of Design No. 16,026, dated April 7, 1885.

Application filed February 7, 1885. Term of patent 7 years.

To all whom it may concern:

Be it known that I, WILLIAM POUNTNEY, of Port Jervis, in the county of Orange and State of New York, have invented and produced a new and original Design for Wine or Bar Bottles, of which the following is a full, clear, and exact description.

Reference is to be had to the accompanying drawing, forming part of this specification, in which the figure is a front elevation of my new design for wine or bar bottles.

The leading features of my design consist of the configuration of a series of raised rings or beads of round or oval form represented in relief upon the bottle, and of the configuration of a series of open-ended elongated loops, also represented in relief.

The illustrated bottle A is circular. *a* refers to the configurated series of raised rings or beads represented in relief near the upper end of the body of the bottle. *b* refers to the configurated series of open-ended elongated

loops, also represented in relief at the lower end of the bottle.

Having thus fully described my invention, I claim as new and desire to secure by Letters Patent—

1. The design for a bottle herein shown and described, the same consisting of the configuration of a series of rings or beads represented in relief.

2. The design for a bottle herein shown and described, the same consisting of the series of open-ended elongated loops represented in relief.

3. The design for a bottle herein shown and described, the same consisting of the configuration of the series of rings or beads and the series of open-ended elongated loops represented in relief.

WILLIAM POUNTNEY.
